(57) **CLAIM**

We claim the ornamental design for a fluid mixer, as shown and described.

DESCRIPTION

FIG. 1 is a perspective view of a fluid mixer comprising the present invention.

FIG. 2 is a left elevational view of the fluid mixer shown in FIG. 1.

FIG. 3 is a right elevational view of the fluid mixer shown in FIGS. 1 and 2.

FIG. 4 is a front elevational view of the fluid mixer shown in FIGS. 1, 2, and 3.

FIG. 5 is a rear elevational view of the fluid mixer shown in FIGS. 1, 2, 3, and 4.

FIG. 6 is a top plan view of the fluid mixer shown in FIGS. 1, 2, 3, 4, and 5.

FIG. 7 is a bottom plan elevational view of the fluid mixer shown in FIGS. 1, 2, 3, 4, 5, and 6.

FIG. 8 is a perspective view of another embodiment of a fluid mixer comprising the present invention.

FIG. 9 is a left elevational view of the fluid mixer shown in FIG. 8.

FIG. 10 is a right elevational view of the fluid mixer shown in FIGS. 8 and 9.

FIG. 11 is a front elevational view of the fluid mixer shown in FIGS. 8, 9, and 10.

FIG. 12 is a rear elevational view of the fluid mixer shown in FIGS. 8, 9, 10, and 11.

FIG. 13 is a top plan view of the fluid mixer shown in FIGS. 8, 9, 10, 11, and 12; and,

FIG. 14 is a bottom plan view of the fluid mixer shown in FIGS. 8, 9, 10, 11, 12, and 13.

The broken lines are for environmental purposes only and form no part of the claimed design.
